US00D877752S

(12) **United States Design Patent** (10) **Patent No.:** **US D877,752 S**
(45) **Date of Patent:** **** Mar. 10, 2020**

(54) **DISPLAY PANEL OR PORTION THEREOF
WITH GRAPHICAL USER INTERFACE**

(71) Applicant: **MAGIC LEAP, INC.**, Plantation, FL (US)

(72) Inventors: **Lorena Pazmino**, Wilton Manors, FL (US); **Karen Stolzenberg**, Fort Lauderdale, FL (US); **Tim Zurmoehle**, Fort Lauderdale, FL (US); **Timothy Michael Stutts**, Oakland Park, FL (US)

(73) Assignee: **MAGIC LEAP, INC.**, Plantation, FL (US)

(**) Term: **15 Years**

(21) Appl. No.: **29/640,733**

(22) Filed: **Mar. 16, 2018**

(51) LOC (12) Cl. **14-04**

CLAIM

The ornamental design for display panel or portion thereof with graphical user interface, as shown and described.

DESCRIPTION

The sole FIGURE is a front view of a display panel or portion thereof with graphical user interface showing our design.

The outermost broken line rectangle illustrates a display panel or portion thereof that forms no part of the claimed design. The remaining broken lines, including all text, illustrate portions of the graphical user interface or a mixed reality environment, and form no part of the claimed design.

1 Claim, 1 Drawing Sheet
